DESCRIPTION

U.S. PATENT DOCUMENTS

FIG. 1 is a front perspective view of a portion of an electronic mouse showing my new design;

D368,900 S	4/1996	Ma
D369,593 S	5/1996	Ma
D373,999 S	9/1996	Staats
D385,861 S	11/1997	Lin
D402,281 S	12/1998	Ledbetter et al.
D411,189 S	6/1999	Liao et al.
D437,852 S	2/2001	Ledbetter et al.
D438,212 S	2/2001	Whitenack
D439,253 S	3/2001	Sheehan et al.
D443,616 S	* 6/2001	Fisher et al. D14/402
D450,321 S	* 11/2001	Fisher et al. D14/402
D450,697 S	* 11/2001	Fisher et al. D14/402
D450,698 S	* 11/2001	Fisher et al. D14/402
D450,699 S	* 11/2001	Fisher et al. D14/402

FIG. 2 is a left side view thereof;

FIG. 3 is a right side view thereof;

FIG. 4 is a front view thereof;

FIG. 5 is a rear view thereof; and,

FIG. 6 is a top view thereof.

The broken line showing of a scroll wheel region is for illustrative purposes and forms no part of the claimed design. The unshown bottom of the electronic mouse forms no part of the claimed design. The difference in shading indicates a contrast of appearance and does not depict any particular color, texture, or material.
